(57) **CLAIM**

The ornamental design for a headset, as shown.

DESCRIPTION

The parts referred to consist of a microphone boom arm and a T-bar which can be mounted on the end of the head spring band.

FIG. 1 is a front and bottom right perspective view showing my new invention;

FIG. 2 is as right side elevation view of FIG. 1;

FIG. 3 is a left side elevation view of FIG. 1;

FIG. 4 is a bottom plane view of FIG. 1;

FIG. 5 is a front elevation view of FIG. 1;

FIG. 6 is a rear elevation view of FIG. 1; and,

FIG. 7 is a top plane view of FIG. 1.
